UNITED STATES PATENT OFFICE.

IRVINE P. BOGGS, OF WHEELING, WEST VIRGINIA.

ARTIFICIAL LIMB.

Application filed November 17, 1927. Serial No. 233,948.

This invention relates to an improved artificial limb which involves a new and dependable knee control action possessing sufficient elasticity and precision in operation,

5 as to render it substantially lifelike in operation.

Briefly, the invention comprises an artificial limb, which embodies a thigh portion, a lower leg portion, and an especially designed knee joint construction, together with manually manipulated means for regulating the activity of the knee joint to permit the lower leg portion to be manipulated at the will of the wearer, to simulate the natural 15 walking of this particular individual.

The particular mechanical details incorporated in the new arrangement will become more readily apparent from the following description and drawings.

20 In the drawings:—

Figure 1 is a fragmentary view with portions broken away and shown in section to disclose clearly the internal structural details, and their relative arrangement and association.

Fig. 2 is a rear view of the structure.

Fig. 3 is a cross section taken approximately upon the plane of the line 3—3 of Fig. 1, looking in the direction of the arrow, and

30 Fig. 4 is a section on the line 4—4 of Fig. 3.

Referring now to the drawings by numerals, it will be observed that the reference character 5 designates generally, the thigh, while the reference character 6 designates the 35 lower leg portion. These portions 5 and 6 are constructed at their meeting ends to provide a novel artificial knee joint including the ball-like portion 7, extending into a correspondingly shaped socket in the leg portion 6.

The portions 5 and 6 are connected together by a pivot bolt 8 fastened at its outer end to the reinforcing straps 9, riveted to opposite sides of the leg sections 6. This arrangement 45 allows the joint to "break" in the usual manner.

It will be noted that a flexible tie 10 is provided, and is looped at its opposite ends around cross pins 11 and 11^a carried by the 50 respective sections, as better shown in Fig. 1. This tie member 10 limits the swinging movement of the lower section 6 in a forward direction.

Attention is now invited to a flexible cord 55 of appropriate texture designated by the numeral 12. This extends from the hollowed

out portion of the thigh section 5 down through an appropriate recess in the leg section 6, where its lower ends are slit as shown in Fig. 2 in dotted lines.

60

The slit portions 13 are anchored as at 14. Fastened to the upper end of this cord 12 is a cross head 15, provided with a pulley 16 over which cables or their equivalents are trained. Incidentally, these cables extend 65 up and connect with a shoulder saddle (not shown), which the user places on the shoulder in a convenient manner. Thus by exerting an upward lift on the shoulder strap or saddle, the wearer can lift up on the head 15, and in turn exert an upward stress upon the 70 cord 12, thus bringing the leg section 6 forward, in an obvious manner.

65

It will be noticed particularly from Fig. 3, that adjusting means is employed for regulating the sensitivity of action of this cord 12, and this means comprises a plate 18 fastened to the bottom of the thigh section, 5 by screws or other fastening means, this plate having guide grooves slidably receiving the 80 flanges 19 on a sliding yoke 20. This yoke carries a small pulley 21 and is mounted for adjustment on the shank of a screw 22.

75

The head of the screw, which passes through an upstanding flange 23, is accessible 85 through an opening 24. In other words, a screw driver can be placed in thru this opening 24, and engaged with the kerf of the head of the screw, to turn the screw to move the yoke 20 back or forth, thus permitting the 90 pulley 21 to be brought in contact with the adjacent portion of the cord 12, as shown plainly in Fig. 1.

80

With this arrangement, the tension on this cord can be regulated, and the action of the 95 lower leg return governed by the wearer.

In operation, it is understood that by anchoring the lower end of the cord 12 to the calf portion of the lower leg section, and by passing it upwardly and over the pulley on 100 the regulating device, as shown in Fig. 1, and by connecting the pull cable 17 to the shoulder saddle, the forward motion of the lower leg section 6 can be controlled by the wearer.

100

Obviously, when weight is brought to bear 105 upon the breakable knee joint, the lower leg section 6 moves rearwardly. Then, as the thigh section 5 is brought forwardly, in taking the next step, the wearer exerts upward pull on the shoulder saddle, which transmits motion to the cord 12 through the medium of the pull cables 17. This therefore exerts a 110

forward thrust upon the lower leg section 6 and returns it to normal position to take the next step.

Therefore, the wearer can manipulate the 5 artificial limb in a manner to simulate natural walking. In addition, he can regulate the activity through the tension device described. It is quite clear how this is accomplished.

Minor changes coming within the invention 10 claimed may be resorted to if desired.

Having thus described my invention, what I claim as new is:—

In an artificial limb of the class described, a 15 thigh section, a lower leg section and a complementary breakable joint between said sections, means for limiting the swinging movement of the lower leg section in a forward

direction, a pivotal connection between said sections, a cord fastened at its lower end with the calf of said lower leg section and extending upwardly and into the thigh section, a head on the upper end of said cord, pulleys carried by said head and pull cables trained over said pulleys, said pull cables adapted to be associated with shoulder operated means, together with manually adjustable tension regulating means mounted in the thigh section, and cooperable with said cords, said last named means including a plate, a yoke 20 25 slidably mounted on the plate, an adjusting screw for the yoke, and a pulley carried by the yoke and cooperable with said cord.

In testimony whereof I affix my signature.

IRVINE P. BOGGS.
